[57] CLAIM

The ornamental design for a hedge trimmer, as shown and described.

DESCRIPTION

FIG. 1 is a top front, and right side perspective view of a hedge trimmer showing my new design;
FIG. 2 is a right side elevational view thereof;
FIG. 3 is a left side elevational view thereof;
FIG. 4 is a front elevational view thereof;
FIG. 5 is a rear elevational view thereof;
FIG. 6 is a top plan view thereof; and,
FIG. 7 is a bottom plan view thereof.

The broken-line disclosure of a blade in the views is for illustrative purposes only and forms no part of the claimed design.

The blade shown in phantom is for illustrative purposes only, and forms no part of the present invention.
